UNITED STATES PATENT OFFICE.

EDGAR B. CAHN, OF FAR ROCKAWAY, NEW YORK.

HOSIERY.

1,136,097.

Specification of Letters Patent. Patented Apr. 20, 1915.

Application filed June 24, 1914. Serial No. 846,965.

To all whom it may concern:

Be it known that I, EDGAR B. CAHN, a citizen of the United States, and resident of Far Rockaway, in the county of Queens and 5 State of New York, have invented certain new and useful Improvements in Hosiery, of which the following is a specification.

The object of my invention is to provide stockings or hose with an openwork or freely 10 vented section or portion located in position over the toes of the wearer, to permit air to circulate freely through such portion, whereby the main portions of the hose may be made of the desired texture, strength and the 15 like for wearing qualities, while the open or vented section at the toe part of the stocking or hose does not unduly detract from the normal strength of the latter.

In carrying out my invention I provide 20 hosiery of any suitable construction with an openwork, porous or vented transverse section at a desired distance back from the toe portion, which open or vented section is suitably knitted with the main portion of the 25 hose, and which section may pass not only across the top of the foot portion over the toes, but may extend down along the sides a suitable distance and down to the sole portion of the hose.

30 A further preferred embodiment of my invention comprises hosiery having a reinforced sole and toe portion, the openwork or vented section next rearwardly thereof, a further reinforced portion next rearwardly 35 of said openwork or vented section, the second named reinforced portion being joined to the ordinary wearing portions of the hose, all of such portions being preferably knitted integrally.

40 Reference is to be had to the accompanying drawings forming a part hereof, wherein,

Figure 1 is a plan view of a stocking embodying my invention; Fig. 2 is a sectional side view thereof, and Fig. 3 is an enlarged 45 detail, in plan, of a portion of the said stocking.

The stocking or sock indicated, generally, at 1, may be knitted or otherwise formed in any suitable way, such as in tubular manner 50 or full-fashioned manner. At the toe portion at a point over the toes of the wearer is an openwork, porous or vented section or portion 2, which is knitted or otherwise made with a series of spaced openings made 55 relatively large to permit free circulation of

air therethrough, said openings being on a scale much more open than the other portions of the hose. The openwork section 2 is shown disposed transversely across the top portion of the hose and down along its 60 sides to a point approximating or slightly above the sole portion, whereby the openings in section 2 permit the free circulation of air downwardly and laterally through the holes. The ventilated or porous section 2 65 may be made integral with the remainder of the hose by suitably knitting the hose in a single piece.

As illustrated in the accompanying drawings the hose is shown provided with the reinforced toe portion 3, rearwardly of which is the ventilated or porous section 2, secured at its forward edge to the rear edge of portion 3, and rearwardly of the section 2 is a reinforced portion 4, secured at its forward 70 edge to the rearward edge of section 2, and having its rear edge secured to the ordinary knitting 5 over the instep portion. The sole portion 6 is shown reinforced and united integrally with the reinforced portions 3, 4, 80 75 the ventilated or porous section 2 at its ends, and the ordinary knitted portion 5.

By means of my improvements a stocking or sock having the ordinary requirements for strength, etc., is provided with the advantage of the open or porous section 2 located as described over the toes of the wearer, whereby the strength of the sock or stocking for use is maintained, and by means of the reinforced section 4 interposed between 85 the openwork section 2 and the main portion 5, the desired strength between the latter section and the toe is provided, notwithstanding the very open or porous like section 2 interposed at the top of the forward portion 90 of the stocking or sock.

Having now described my invention what I claim is:—

1. A stocking or hose having a reinforced upper front toe portion, a porous or open section extending transversely along the top and united at its forward edge to said reinforced upper front portion and at its ends to the sole portion, and having a reinforced portion behind said section that is united 100 105 at its forward edge to the rear edge of said section and united at its rear edge to the forward edge of the foot portion.

2. A stocking or hose knitted integrally and having a reinforced sole and upper front 110

toe portion, a porous or open section extending transversely along the top behind said reinforced toe portion and united thereto and to the reinforced sole portion, and a reinforced portion behind the porous or open section that is united thereto and to the reinforced sole portion.

Signed at New York city, in the county of New York and State of New York, this 23rd day of June, A. D. 1914.

EDGAR B. CAHN.
